UNITED STATES PATENT OFFICE.

FRANK M. LEAVITT, OF SMITHTOWN, NEW YORK, ASSIGNOR TO E. W. BLISS COMPANY, OF BROOKLYN, NEW YORK, A CORPORATION OF WEST VIRGINIA.

SINKING DEVICE FOR AUTOMOBILE TORPEDOES.

1,076,295.

Specification of Letters Patent.

Patented Oct. 21, 1913.

Application filed January 3, 1913. Serial No. 739,892.

To all whom it may concern:

Be it known that I, FRANK M. LEAVITT, a citizen of the United States, residing in Smithtown, in the county of Suffolk and State of New York, have invented certain new and useful Improvements in Sinking Devices for Automobile Torpedoes, of which the following is a specification.

This invention relates to automobile torpedoes and its object is to provide means for causing the torpedo to sink in case, when used in actual warfare, it makes an unsuccessful run, in order that the torpedo shall not be a source of danger to navigation. Its object also is to provide means whereby, in the use of the torpedo for practise or exercise runs, the sinking of the torpedo shall be prevented in order that it may be readily recovered after the run.

20 In the well known Bliss-Leavitt torpedo the propeller screws are driven by a turbine engine which is driven by compressed air. The exhaust air from this engine is discharged into the after-body from which it 25 escapes through the hollow propeller shaft, being discharged from the open end of this shaft at the stern.

In my Patent No. 748,759, dated January 5, 1904 is shown a construction wherein 30 the escaping air forces open a spring-closed exhaust valve which closes automatically when the flow of air ceases at the end of the run, thus preventing any inflow of water and imprisoning the remaining air so as to 35 give the torpedo sufficient buoyancy to cause it to rise to the surface after the run so that in the case of practise runs it may be easily recovered.

The present invention provides spring-40 closed exhaust valves differently constructed and arranged, and provides means in connection therewith for preventing the closing of these valves when once opened by the exhaust, so that when such means is operative 45 the valves cannot close at the end of the run, and hence water may flow in to sink the torpedo. For a practise run, however, such means is incapacitated whereby to insure that the valves shall close when the out-50 flow of air ceases and thereby imprison the remaining air and maintain the torpedo buoyant so that it shall float to the surface.

In the accompanying drawings Figure 1 is an elevation of the tail portion of a tor-55 pedo, a portion of the after-body being

broken away in vertical section. Fig. 2 is a fragmentary longitudinal section in an oblique plane shown by the lines 2-2 in Fig. 3. Fig. 3 is a transverse section. Figs. 4 and 5 are sectional detail views.

60 In the drawings A is the torpedo shell or hull having a transverse bulkhead B. This bulkhead is commonly at the rear end of the after-body A' where it joins the tail section A². Through the bulkhead B passes the propeller shaft C carrying the forward propeller screw D, while within this shaft is the inner shaft C' carrying the aft screw D'. In the bulkhead B are formed one or more exhaust openings E, preferably two as shown, each of which is provided with a valve F. Each valve F is provided with a spring G for closing it. Each valve is best mounted on a lever H pivoted at I and connected by a link J to a rod K which receives the thrust of the spring against its head K', the counter-thrust being exerted against the internal shoulder L' in a tubular shell L, which is fastened to the bulkhead B and conveniently projects forwardly inside the after-body. The arrangement is such that when the spent compressed air exhausts from the engine or turbine into the after-body and presses against the valves F, they will be unseated and permit the air to escape into the tail section and thence to the exterior, or preferably by entering holes a a in the shafts C C' and passing through the inner shaft to the stern where the air escapes at the open end b. This provision for the escape of the air is more fully set forth in my pending application No. 716,189, filed 75 August 21, 1912.

90 At the end of the run if it be a practise run, the springs G will draw the valves F to their seats, thereby closing the exhaust openings E and imprisoning the air in the after-body and preventing the ingress of water thereto, whereby the torpedo is maintained sufficiently buoyant to float to the 95 surface. In the case of a service run, however, as in actual warfare, one of the valves F F is to be held unseated so that at the end of the run water may freely enter the after-body and sink the torpedo. To accomplish this I provide a spring-pressed dog M having a toe N which is adapted to enter between the valve F and its seat and thereby prevent the re-seating of the valve. The dog M is best formed as a 2-armed lever, 100 105 110

one arm carrying the toe N, the other arm O projecting in the contrary direction, and the middle part of the lever formed as a tubular sleeve or hub M' which is pivoted on a stud P around which is coiled a spring Q, one end of which is connected to the dog M and the other to the stud P in such manner as to impart to the dog a tendency to move in such direction as to thrust its toe N under the valve F.

Before the launching of the torpedo the valves F are seated, the dog M having been displaced so that its toe N presses against the rim of the valve. As soon as the valve is opened by the air pressure the stress of the spring pushes the toe end of the dog in between the valve and its seat where it remains from that time.

In order to incapacitate this sinking device so that the torpedo may be used for practise runs, either the dog M may be removed by unshipping it from the pivotal stud P or, preferably, some stop may be interposed to hold it pressed back so that the toe N cannot enter under the valve. It is to facilitate this that the arm O is provided which may be pressed down by a stop of any suitable kind such, for example, as a screw stud R, Fig. 5, which may be introduced through the shell from the exterior, screwing into a threaded socket R' whereby to hold the dog M in its inactive position against the stress of its spring.

The described construction of valves F with their lever mountings and spring arrangement is a desirable detail of my invention.

I claim as my invention:—

1. In an automobile torpedo, a spring-closed exhaust-valve opening from an air chamber within the shell, and means for holding said valve open when it has been opened by the escaping air to admit water to said chamber after the run to sink the 45 torpedo.

2. In an automobile torpedo, a spring-closed exhaust-valve opening from an air

chamber within the shell, and means for holding said valve open when it has been opened by the escaping air, said means adapted to be manually rendered inoperative at will. 50

3. In an automobile torpedo, a spring-closed exhaust-valve opening from an air chamber within the shell, and means for holding said valve open when it has been opened by the escaping air consisting of a spring-pressed dog engaging the rim of the valve and adapted to spring between it and its seat upon the opening of the valve. 55

4. In an automobile torpedo, a spring-closed exhaust-valve opening from an air chamber within the shell, and means for holding said valve open when it has been opened by the escaping air, consisting of a spring-pressed dog engaging the rim of the valve and adapted to spring between it and its seat upon the opening of the valve, and means for manually rendering said dog inoperative at will comprising a stop device 65 to hold it retracted against the stress of its spring. 70

5. In an automobile torpedo having a transverse bulkhead with an exhaust opening through it, an exhaust valve to close said opening, a lever engaging said valve, a link connected to said lever and a spring pressing upon said link to close said valve. 75

6. In an automobile torpedo having a transverse bulkhead with an exhaust opening through it, an exhaust valve to close said opening, a lever engaging said valve, a link engaging said lever, a tubular shell into which said link projects, and a coiled spring seated in said shell and pressing against 80 said link to close the valve. 85

In witness whereof, I have hereunto signed my name in the presence of two subscribing witnesses.—

FRANK M. LEAVITT.
